TEXTILE FIBRE BLENDING AND DISTRIBUTING APPARATUS AND METHOD

John H. Senior, Germantown, Pa., assignor to Proctor & Schwartz, Inc., Philadelphia, Pa., a corporation of Pennsylvania

Application March 21, 1947, Serial No. 736,383

11 Claims. (Cl. 19—65)

1

This invention relates to apparatus and method for blending textile fibres, and more particularly to a novel apparatus and method whereby fibres of different qualities, lengths and colors may be mechanically handled and mixed or blended into an effective homogeneous mass for subsequent carding, spinning or other processing.

The practice generally followed in the trade for mixing and blending textile fibres consists in blowing the fibres into a large room or enclosure in which one or more men are located for the purpose of manually spreading the fibres over the floor of the room and in that way effecting a general mixing and blending of them, and when a particular mixing and blending operation such as this had been completed the workers in the room manually gather up the mixed and blended fibres by the armful and convey them, for example, to a chute or hopper by means of which the fibres are delivered to a storage bin or room until ready for further processing or use.

This practice for mixing and blending textile fibres presents certain substantial objections and disadvantages. In the first place, the manual spreading and intermixing of the fibres in a room by workers in the manner described produces a relatively inefficient blending of the fibres which is lacking in homogeneity. Furthermore, the operation is a purely manual one and considerable time and labor cost is consumed. Apart from this, however, there is a substantial health factor involved because the atmosphere of the room or enclosure into which the textile fibres are blown and manually mixed and blended soon becomes heavily laden with dust particles from the fibres to an extent that in many cases it becomes hazardous for persons to continue to work in the blending rooms.

With the foregoing in mind, one object of the present invention is to provide a novel apparatus and method whereby fibres of different qualities, lengths or colors may be satisfactorily mixed, blended and distributed in a single operation.

Another object of the invention is to provide a novel apparatus and method as set forth which is operable mechanically and automatically to blend and distribute textile fibres without the use of manual labor.

These and other objects of the invention and the various features and details of the construction and use thereof are hereinafter fully set forth and described with reference to the accompanying drawings, in which:

Figure 1 is a longitudinal section through a series of fibre blending elements constructed and arranged in accordance with the invention;

Fig. 2 is a similar section showing the elements in different position;

Fig. 3 is a plan view, in greater detail, showing the feed end of such a fibre blending apparatus;

2

Fig. 4 is an elevation of that part of the apparatus shown in Fig. 3;

Fig. 5 is a plan view of the opposite end of the apparatus shown in Fig. 3;

Fig. 6 is an elevation of that part of the apparatus shown in Fig. 5;

Fig. 7 is an enlarged fragmental elevation of a part of the apparatus shown in Fig. 6, viewed as illustrated by the arrows 7—7 in Fig. 6; and

Fig. 8 is a semi-diagrammatic view showing the elements and connections of the motor driving and reversing arrangement.

According to the present invention, a mass of fibre is spread upon a train of rolls which mix and blend the mass by breaking it into segments and rolling each segment downwardly between pairs of adjacent rolls into a blending and storage bin beneath the rolls.

In the drawings there is shown a fibre blending conveyor 10 disposed above a storage and blending bin 11 into which the conveyor periodically discharges. A feed conveyor 12 of the belt type, having substantially the width of the blending conveyor, supplies fibre to the blending conveyor.

The feed conveyor is supported in the usual manner by an idler roller 13 and a driver roller 14 which is driven, as by a sprocket connection 15 from the blending conveyor 10. The fibre is fed from the picker (not shown) to the feed conveyor in a narrow stream, and it is necessary to spread the mass of fibre substantially uniformly across the feed conveyor in order that its supply may cover the entire width of the blending conveyor. Accordingly, a number of spaced spreading fingers 16 are pivoted as at 17 at the receiving end of the feed conveyor. The spreading fingers are caused to sweep back and forth across the supply end of the feed conveyor in order to spread the mass of fibre thereon. To this end, each spreading finger is pivotally connected to an actuating rod 18, which is reciprocated by a bell-crank lever 19, a rod 20, and a sprocket wheel 21, all suitably connected together and driven from the driver roller 14 of the feed belt.

The fibre blending conveyor 10 comprises a train or series of parallel uni-directional rolls 22 and bi-directional rolls 23 alternately spaced and closely juxtaposed. The rolls may be made of sheet metal, or of any other known or convenient material, and longitudinal fins 24 extend radially from the peripheries of all rolls. The rolls are carried by horizontal axles which are journaled at either end above the longitudinal side walls of the storage bin 11 and so spaced that small clearance is allowed between the longitudinal fins of adjacent rolls. See Figs. 1 and 2.

In order to rotate the uni-directional rolls 22 of the fibre blending conveyor in a direction which 60 will carry the mass of fibre away from the feed

conveyor and the feed end of the series of rolls, bevel gears 25 are fixed to like ends of the uni-directional roll axes. Meshing bevel gears 26 are fixed to a shaft 27 which is driven from a uni-directional motor 28 conveniently positioned adjacent the fibre blending conveyor.

The alternately-spaced bi-directional rolls 23 are similarly driven. Thus bevel gears 29 are fixed to the ends of the bi-directional roll axes on the opposite side of the conveyor from that of the uni-directional drive, and meshing bevel gears 30 are fixed to a drive shaft 31, which is driven from a bi-directional motor 32. Means, later to be described, reverses the bi-directional motor periodically at pre-determined intervals.

Accordingly all rolls are first driven away from the belt conveyor 12 and the feed end of the series of rolls, and when the mass of fibre covers the entire blending conveyor 10, (see Figure 1) the bi-directional rolls 23 are reversed to discharge the fibres between pairs of rolls. Reversal of the bi-directional rolls separates the fibre mass into segments as best shown in Fig. 2. The fibres of each segment are drawn by the longitudinal fins 24 from either side between the rolls. The fibres are thus mixed and blended as they are drawn from outside positions to a central position between a pair of rolls, and they are further mixed and blended as they pass between the rolls, expand, and fall freely into the bin 11.

Thus the fibres are fed to one end of a series of parallel, juxtaposed cylinders: namely, the rolls 22 and 23 of the blending conveyor. All of the cylinders are then rotated away from the feed end of the series, and the direction of rotation of alternate cylinders is periodically reversed to discharge the fibres between adjacent cylinders into a container: namely, the bin 11, in mixed and blended condition.

The means for operating the drive shafts 27 and 31, including one means for reversing the bi-directional motor, will now be described. Referring to Fig. 8, a source of direct current is illustrated by poles 33 and 34.

Suitable connections are provided whereby the uni-directional motor may be driven from the source of direct current. Thus, from the pole 33, a lead 35 extends to a junction point 36, whence a wire 37 connects with the uni-directional motor 28. A second lead 38 passes from the pole 34 through a normally-open, main switch 39 and connects with a second junction point 40, whence a wire 41 completes the circuit through the uni-directional motor. With the main switch 39 closed, therefore, the motor 28 will be energized and will continue to drive the shaft 27 in pre-determined direction.

The main switch 39 is of normally-open type, solenoid-operated, and of conventional construction. It closes the circuit by moving a contact bar 42, to bridge terminals 43 and 44 where the continuity of the lead 38 is broken. A normally-open control switch 45 is used to close the main switch 39, closing a shunt circuit from a junction point 45, between the pole 34 and the adjacent terminal 43 of the main switch 39, through a solenoid 47 to a connection 48 on the lead 35. The solenoid, thus energized, closes the main switch.

In the absence of other connections, when the normally-open control switch 45 is released the shunt circuit will be broken, the solenoid will be de-energized, and the main switch will open. In order to keep the solenoid energized until it is desired to stop the motor, an auxiliary circuit is provided for the solenoid 47 which is closed when

the main switch is closed and which maintains energization of the solenoid until this auxiliary circuit is broken.

Thus the auxiliary circuit is connected to the lead 38, beyond the main switch 39, as at 49, includes a normally-closed release switch 50, and auxiliary terminals 51 and 52, and a connection 53 from the terminal 52 to the control circuit between the control switch and the solenoid. An auxiliary contact bar 54, operates with the main switch contact bar 42 to bridge the auxiliary terminals 51 and 52.

Accordingly, when the control switch 45 is closed and the solenoid closes the main switch, the auxiliary circuit is also closed through the solenoid. When the control switch is released, the control circuit is broken, but the auxiliary circuit continues to energize the solenoid and keeps the main switch closed. Operation of the release switch 50 breaks the auxiliary circuit, de-energizes the solenoid, and the normally-open main switch opens.

Closing the main switch 39 also energizes the reversing motor 32, the direction of which is determined by a timer 55, later to be described.

The reversing motor is energized through a wire 56 connected thereto and to the lead 35 which it joins as at 57; and in alternate directions by wires 58 and 59 which are oppositely connected to the reversing motor 32 and to contact points 60 and 61 respectively upon the timer 55. The timer is in turn connected to the lead 38.

The timer 55 here shown comprises a pivoted contact arm 62 which is conveniently connected, as at its pivot, to the lead 38. A cam 63, rotated by a motor 64, oscillates between the contact points 60 and 61. The motor 64 is energized from the leads 35 and 38 to which it is connected as by wires 65 and 66 joined to the leads 35 and 38, as at 36 and 40.

The contact arm 62 is held against one of the contact points, as the contact point 61, in any convenient manner, as by a helical spring (not shown) at its pivot point. The cam 63, rotated by the motor 64, periodically passes over a roller 67 upon the contact arm and moves the latter from its position against the contact point 61 to a position against the contact point 60, thereby breaking the connection through the wire 59 and making a connection through the wire 58 to reverse the motor 32. As the cam 63 continues to rotate the contact arm moves back against the contact point 61 and the motor is again reversed. Obviously the contact arm 67 will remain against the contact point 61 during most of the rotation of the cam 63 and this position of the contact arm therefore corresponds to forward movement of the bi-directional rolls 23.

The peripheral length of the cam 63, the form of its operating projection, and the rate at which the motor 64 rotates it are so designed that the contact arm 62 will be held against the contact point 61 for a length of time corresponding to that required by the rolls 22 and 23 to move the initial end of a new mass of fibre from the feed end of the roll train to the far end thereof. The number of revolutions of each roll before the bi-directional rolls are reversed will therefore be equal to the length of the roll train divided by the peripheral length of an individual roll; and the gear ratios, cam design, and timer motor speed may be figured accordingly. The length of time during which the direction of the bi-directional rolls is reversed will of course depend upon the length of time during which the con-

tact arm is held against the contact point 60 and will therefore depend upon the timer motor speed and cam design.

To avoid strain upon the reversing motor 32 during reversal, a conventional brake mechanism is employed. Thus there is operatively associated with the reversing motor 32 a brake 68 which is actuated by a spring 69, normally to brake the motor. When the motor is energized through the wire 58, a shunt circuit energizes a solenoid coil 70, thereby causing a connected arm 71 to neutralize the action of the spring 69 and release the brake 68. The instant the contact arm 62 loses contact with the contact point 60, the solenoid coil 70 is de-energized, releases the arm 71, and the spring 69 again applies the brake to the motor. Correspondingly, when the contact arm 62 engages the contact point 61 to energize the motor in the opposite direction, a shunt circuit energizes a solenoid coil 72 thereby causing the arm 71 to neutralize the spring 69 and release the brake 68. Accordingly, each time the direction of the reversing motor 32 is changed the inertia of the motor is braked before the reverse energizing current is applied.

Returning now to the blending and storage bin 11, into which reversal of the bi-directional rolls 23 causes the mass of fibre upon the train of rolls to drop, means is provided for periodically removing the mass of fibre from the bin when the bin has become filled, or at any other desired time. Thus, a belt conveyor 73 is disposed in the bottom of the bin, extending over its entire width and movable from one end of the bin to the other, and beyond the bin, to carry the contents out of the bin. Thus the belt conveyor 73 is carried at one end by an idler roller 74 and at the other end by a drive roller 75, belt-driven through gears 76 and 77 from a drive box 78 conveniently disposed. The belt conveyor 73 removes the stock from the bin at the right hand end thereof, as best seen in Fig. 6. The train of rolls above the bin may be stopped when this operation is being performed.

Furthermore, means is provided for additionally breaking down the high mass of stock contained in the bin as it leaves the bin. One such means comprises retractable pin rolls 79 and 80, which may be constructed in accordance with Patent No. 2,372,543, granted to William F. Bokum, March 27, 1945, for "Stripping roll for long fibre feeders." The retractable pin rolls 79 and 80 are preferably belt driven from the drive box 78, and at different speeds. The lower roll 80 revolves at higher speed than the upper roll 79, and both rolls together serving to thin and break down the high mass of fibre in the bin as it leaves the bin on the conveyor 73.

From the foregoing it will be apparent that heterogeneous masses of fibre carried to the feed belt will be distributed thereon by the spreading fingers, will be fed in a layer of substantially uniform thickness completely across the fibre blending conveyor. Broken into segments and discharged between adjacent rolls of the fibre blending conveyor, the fibre will fall into the blending and storage bin. Thus, fibres of different qualities and lengths may be satisfactorily mixed and blended in a single operation. Furthermore, the operation is mechanical and does not require expensive manual labor.

The form of the invention which is described in this specification and illustrated in the accompanying drawings is set forth merely to indicate how the invention may be applied. Other forms,

variations, and embodiments of the invention, coming within the proper scope of the appended claims, will naturally suggest themselves to those skilled in the art.

I claim:

1. Fibre blending apparatus comprising a series of parallel juxtaposed rolls, driving means coupled to alternate rolls of said series for rotating them in one direction, and reversible driving means coupled to the remaining rolls of said series for rotating them alternately in two directions, whereby a mass of fibre, placed upon the end of said series of rolls away from which all rolls rotate, will first be carried along said series of rolls and will then be discharged between pairs of rolls in mixed condition.

2. Fibre blending apparatus comprising a series of parallel juxtaposed rolls, a conveyor for feeding fibre to one end of said series of rolls, driving means coupled to alternate rolls of said series for rotating the alternate rolls away from the feed point of said conveyor, and reversible driving means coupled to the remaining rolls of said series for rotating them alternately away from the feed point of said conveyor and toward the feed point of said conveyor, whereby a mass of fibre, fed to said series of rolls by said conveyor, will first be carried along said series of rolls and will then be discharged between pairs of rolls in mixed condition.

3. Fibre blending apparatus comprising a series of parallel juxtaposed rolls, longitudinal fins extending radially from the peripheries of said rolls, a conveyor for feeding fibre to one end of said series of rolls, driving means coupled to alternate rolls of said series for rotating the alternate rolls away from the feed point of said conveyor, reversible driving means coupled to the remaining rolls of said series for rotating them alternately away from the feed point of said conveyor and toward the feed point of said conveyor, and reversing means for reversing the direction of said reversible driving means when the rolls of said series have rotated a linear distance substantially equal to the length of said series of rolls, whereby a mass of fibre, fed to said series of rolls by said conveyor, will first be carried along said series of rolls to cover the rolls substantially completely, and will then be discharged between pairs of rolls in mixed condition.

4. Fibre blending apparatus comprising a series of parallel juxtaposed rolls, driving means coupled to alternate rolls of said series for rotating them in one direction, and reversible driving means coupled to the remaining rolls of said series for rotating them alternately in two directions, in combination with a blending and storage bin beneath said series of rolls, and a conveyor extending over the bottom of and movable beyond said bin, whereby a mass of fibre, placed upon the end of said series of rolls away from which all rolls rotate, will first be carried along said series of rolls, will then be discharged between pairs of said rolls in mixed condition into said bin, and will be removed mechanically from said bin.

5. Fibre blending apparatus comprising a series of parallel juxtaposed rolls, a conveyor for feeding fibre to one end of said series of rolls, driving means coupled to alternate rolls of said series for rotating them away from the feed end of said series of rolls, and reversible driving means coupled to the remaining rolls of said series for rotating them away from the feed end of said series of rolls to coact with the alternate rolls of said series to cover the rolls with fibre and toward

the feed end of said series of rolls to discharge fibre from said series of rolls between alternate pairs of rolls, in combination with a blending and storage bin beneath said series of rolls for receiving fibre discharged from said series of rolls, a conveyor extending over the bottom of and movable beyond said bin for periodically removing fibre from said bin, and retractile pin rolls disposed adjacent the point where said conveyor moves beyond said bin for thinning and breaking down the mass of fibre in said bin as said conveyor removes fibre from said bin.

6. Fibre blending apparatus comprising a series of parallel juxtaposed rolls, longitudinal fins extending radially from the peripheries of said rolls, a conveyor for feeding fibre to one end of said series of rolls, driving means coupled to alternate rolls of said series for rotating them away from the feed end of said series of rolls, reversible driving means coupled to the remaining rolls of said series for rotating them away from the feed end of said series of rolls to coact with the alternate rolls of said series to cover the rolls with fibre and toward the feed end of said series of rolls to discharge fibre from said series of rolls between alternate pairs of rolls, and reversing means for reversing the direction of said reversible driving means when the rolls of said series have rotated a linear distance equal to the length of said series of rolls, in combination with a blending and storage bin beneath said series of rolls for receiving fibre discharged from said series of rolls, a conveyor extending over the bottom of and movable beyond said bin for periodically removing fibre from said bin, and retractile pin rolls disposed adjacent the point where said conveyor moves beyond said bin for thinning and breaking down the mass of fibre in said bin as said conveyor removes fibre from said bin, substantially as described.

7. A fibre blending conveyor comprising a train of rolls for advancing fibre along said conveyor in one direction, a driving connection coacting with alternate rolls of said train for rotating them in one direction, a second driving connection coacting with the remaining rolls of said train for rotating them in like direction, and reversing mechanism coacting with said second driving con-

nexion for periodically reversing its direction to discharge fibre from said conveyor between adjacent rolls thereof in mixed condition.

8. A fibre blending conveyor comprising a train of rolls for advancing fibre along said conveyor in one direction, longitudinal fins extending radially from the peripheries of said rolls, a driving connection coacting with alternate rolls of said train for rotating them in one direction, a second driving connection coacting with the remaining rolls of said train for rotating them in like direction, and reversing mechanism coacting with said second driving connection for periodically reversing its direction to discharge fibre from said conveyor between adjacent rolls thereof in mixed condition.

9. A fibre blending conveyor comprising a train of rolls for advancing fibre along said conveyor in one direction, a driving connection coacting with alternate rolls of said train for rotating them in one direction, a second driving connection coacting with the remaining rolls of said train for rotating them in like direction, reversing mechanism coacting with said second driving connection for periodically reversing its direction to discharge fibre from said conveyor between adjacent rolls thereof in mixed condition, and a timer for actuating said reversing mechanism when the rolls of said train have rotated in fibre-advancing direction a linear distance equal to the length of said series of rolls.

10. A method of blending fibres comprising feeding the fibres to one end of a series of parallel juxtaposed cylinders, rotating all cylinders in a direction away from the feed end of the series and periodically reversing the direction of rotation of alternate cylinders to discharge the fibres between adjacent cylinders.

11. A method of blending fibres comprising spreading fibres on a surface, feeding the spread fibres from the surface to one end of a series of parallel juxtaposed cylinders, rotating all cylinders in a direction away from the feed end of the series, and periodically reversing the direction of rotation of alternate cylinders to discharge the fibres between adjacent cylinders into a container.

JOHN H. SENIOR.
